UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

CONVERTIBLE STOCK CAR.

Application filed January 30, 1922. Serial No. 532,735.

To all whom it may concern:

Be it known that I, ARGYLE CAMPBELL, a citizen of the United States, residing at Chicago, in the county of Cook and State of Illinois, have invented a certain new and useful Improvement in Convertible Stock Cars, of which the following is a full, clear, concise, and exact description, reference being had to the accompanying drawings, forming 10 a part of this specification.

This invention relates to improvements in convertible stock car.

One object of the invention is to provide a stock car which may be readily converted 15 for the carrying of coal or other like commodities in bulk without danger of loss of the load due to leakage, to the end that the car will produce greater revenue for the railroad company.

20 Other objects of the invention will more clearly appear from the description and claims hereinafter following.

In the drawings forming a part of this specification, Figure 1 is a side elevational 25 view of approximately one half of a convertible stock car showing my improvements in connection therewith, the upper portions of the car being omitted. Figure 2 is a horizontal, sectional view of a car embodying 30 my improvements, part of the floor doors being shown in their horizontal position and part in their vertical position as the same would be employed when the car is carrying coal or other commodities in bulk. Figure 3

35 is a vertical, longitudinal, sectional view taken at the center of the car and looking to one side thereof and showing the position assumed by certain of the parts when the car is employed for carrying coal or like 40 bulk commodities. Figure 4 is an enlarged, vertical transverse, sectional view of the car corresponding substantially to the section line 4—4 of Figure 1. Figure 5 is a side, vertical sectional view corresponding to the 45 section line 5—5 of Figure 3 but upon somewhat larger scale. And Figure 6 is a detail, sectional view corresponding to the section line 6—6 of Figure 3.

The improved stock car, as shown, is provided with center sills 10, bolsters 11, needle 50 beams 12—12, side sills 13, reinforced end walls 14, and fixed floor sections 15 at each end of the car and preferably extending to points between the trucks.

55 Intermediate the fixed floor sections 15,

the bottom of the car is designed for dumping purposes and to this end, the floor is completed by three floor doors on each side of the center sill, the same comprising two end relatively short floor doors A—A and 60 a middle relatively long floor door B, the latter extending across the usual side door opening of the car. As clearly shown in Figure 4, each of the floor doors is pivoted along its outer edge on a level with the fixed 65 floor of the car as by means of T-headed pivot-forming bolts 16 and slotted hinge straps 17 so that the floor doors are adapted to assume either the horizontal position shown in full lines in Figure 4 or the dotted 70 line vertical position shown in the same figure. When in horizontal position, the floor doors are supported along their free edges by a cover plate 18 secured to the tops of the center sills. Each floor door preferably consists of a plurality of transversely 75 extending planks with suitable binding strips along their pivoted and free edges and angle braces 19 secured to the under sides as shown in Figures 2 and 4.

The car sides are formed by a series of horizontally and longitudinally extending slats 20—20 secured to and braced by suitable posts 21 and diagonal braces 22 on their outer sides. The slats 20 are left with spaces 80 indicated at 23—23 therebetween of preferably 2 $\frac{1}{2}$ " in order to provide ample space for the circulation of air for the stock transported in the car.

I have shown a simple means for holding the floor doors A and B in their vertical position, said means comprising loops 24 carried by the doors and so located that, when the doors are in vertical position, the loops may be pulled outwardly through the 90 corresponding space 23 and pivoted latches 25 entered within the loops on the outer side of the slats, the latches being pivoted to the slats, as best indicated in Figures 1 and 4. When the floor doors are in their 95 horizontal position, the loops 24 drop downwardly so as to avoid presenting any obstruction, the floor doors being sufficiently spaced above the drop doors C to allow of this.

To provide for dumping of the load, I employ a series of dump doors C, eight in number and located beneath the floor doors A and B. Each drop door C is pivotally supported along its inner edge on the center sill 110

by means of suitable hinge butts 26, the outer free edges of the drop doors being sustained by a suitable door operating mechanism, best shown in Figure 4. For each side of the car, 5 the door operating mechanism comprises a longitudinally extending shaft 27 and two sets of linkages 28 for each door, each set of linkages terminating in an elongated link 29 slidably mounted within a suitable housing 30 secured to the under side of the door. Anti-friction rollers 31 are preferably employed on each link 29 as shown in Figure 10 4. The housings 30 are preferably extended the full width of the door to brace the latter 15 and also provide a means for attaching the door hinge strap.

From the preceding description, it will be seen that, when the floor doors A and B are in their vertical position as shown by dotted 20 lines in Figure 4, the spaces between the slots of the car side are covered between the fixed floor sections of the car, thereby adapting the car for the carrying of coal or other bulk commodities without danger of leakage 25 age through the side walls of the car where covered by the said floor doors.

To close the spaces between the slats of the car side walls opposite the fixed floor sections 15 of the car, I employ the following 30 arrangement. On each side of the car, opposite each fixed floor section 15, I employ preferably two lattice doors each designated generally by the reference character D. The lattice doors D are arranged one above the other as clearly shown in Figures 3 and 4. Each of said lattice doors D preferably comprises three longitudinally and horizontally extending bars 32 held together in proper spaced relation by four hinge straps or plates 40 33 and diagonal braces or battens 34. As shown in Figures 4 and 5, the bars 32 are of such size and so located that, when the lattice doors D are in their depending vertical position, the bars 32 will register with and fill 45 three corresponding spaces 23 between slats of the car side wall, thereby effectively sealing the car side and adapting these portions thereof for carrying coal or other bulk commodities without danger of leakage.

50 The hinge straps or plates 33 are pivotally connected at their upper ends to suitable hinge brackets 35—35 carried by the corresponding slats of the car side wall, the pivotal axis of each lattice door being so located that, when the door is swung upwardly 55 above the hinge point, as shown in Figure 4, the bars 32 will overlie the slats of the car side wall without narrowing the spaces between the slats. It will also be noted that 60 the bars 32 of the lattice doors lie directly against the slats of the car side and hence are adapted to strengthen the latter against outward bending and in fact, serve as rump rails for cattle of different height, as will 65 be understood by those skilled in the art.

With this arrangement I am enabled to leave wide spaces between the slats necessary for circulation of air for the cattle and at the same time adapt the car for carrying coal or other bulk commodities without danger of 70 leakage.

As hereinbefore mentioned, the bars 32 of the lattice doors, which bars are preferably of wood, lie directly against the slats of the car sides. It is also desirable that the hinge plates and diagonal braces 34 also lie directly against the slats so as to further brace the latter against outward pressure. To this end, the bars 32 are notched as indicated best in Figure 6 at 36, to receive the hinge plates 33 flush therewithin. The hinge plates 36 are of channel cross section, as shown in Figure 6, with the flanges of the channel facing toward the interior of the car when the lattice doors are in their lower 80 positions as shown in Figure 3. On the back side of the web of each channel hinge plate 33 where the latter passes the bars 32, are provided shallow flanges or shoulders 37 at right angles to the flanges of the channel hinge strap, said shallow flanges or shoulders 37 being received in corresponding rabbets of the bars 32 so as to minimize any danger of the bars 32 shifting longitudinally 85 of the car, that is, transversely of the hinge 90 straps. The bars 32 are also suitably notched to accommodate the diagonal braces 35 flush therewithin so that both the braces and hinge straps and also the bars 32 will bear 95 against the slats of the car side when the 100 lattice doors D are in their uppermost positions.

I have shown two lattice doors for each section of the side wall of the car since they are more easily manipulated in small units 105 but obviously a single lattice door might be employed in lieu of each pair, without departing from the spirit of the invention.

I have herein shown and described what I now consider the preferred manner of carrying out the invention, but the same is merely illustrative and I contemplate all changes and modifications that come within the scope of the claims appended hereto.

I claim:

1. In a convertible, spaced slat side stock car having fixed floor sections, dumping doors, floor doors over the dumping doors and movable to upright position against the sides of the car to cover the latter opposite the dumping doors; lattice doors pivoted along their edges to the car sides opposite the fixed floor sections, and adapted to swing through an arc of approximately 180°, said lattice doors, in one position having the bars 120 thereof nesting between the slats of the car sides and, in another position, having the bars thereof overlying the slats of the car sides.

2. A convertible stock car having, in com- 130

bination: side walls composed of vertically spaced longitudinally extending slats; and lattice doors pivoted to said side walls on the interior thereof, each of said doors comprising a plurality of longitudinally extending bars separated to correspond with and fit within spaces between the slats of the car sides when the door is in one position, said bars overlying the car side slats when the door is swung to a different position through an arc of substantially 180° and, in the latter position, said bars reinforcing the slats to resist outward pressure.

3. A convertible stock car having, in combination: side walls composed of vertically spaced longitudinally extending slats; and lattice doors pivoted to said side walls on the interior thereof, each side door comprising a plurality of hinge straps, the ends of said straps being pivotally supported from a slat of the car side, the bars of each lattice door being separated to correspond with and fit within the spaces between the slats of the car side when the door is in one position, said lattice doors being pivotally movable through an arc of approximately 180° to another position leaving the spaces between the slats of the car side open.

4. A convertible stock car having, in combination: side walls composed of vertically spaced longitudinally extending slats; and lattice doors pivoted to said side walls on the interior thereof, each said lattice door comprising a plurality of longitudinally extending bars, a plurality of hinge straps at right angles to the bars and to which the latter are secured, and diagonal braces between the hinge straps and secured to the bars, said hinge straps and diagonal braces being countersunk flush within the bars.

5. In a convertible stock car, the combination with slotted side walls, fixed floor sec-

tions at the ends of the car, and a dumping section intermediate the fixed floor sections; of floor doors over the dumping section, each of said floor doors being pivotally mounted along its outer edge and adjacent the car side and adapted to be swung to vertical position against the inner side of the car side; and means for holding said floor doors in vertical position comprising, loops attached to the floor doors and adapted to be extended through one of the spaces of the car side, and latches pivotally mounted on the exterior of the car adapted to enter said extended loops.

6. A convertible stock car of the character described comprising: spaced slat side walls; fixed end floor sections; a dumping section intermediate the fixed floor sections and including pivoted dump doors; floor doors adapted to cover the dumping section, the floor doors being pivotally mounted along their outer edges adjacent the car side and adapted to be swung upwardly to cover the car sides; and means for sealing the car sides opposite said fixed floor sections, said means comprising upper and lower sets of independently pivotally mounted lattice doors, each lattice door including a plurality of longitudinally extending spaced bars adapted to enter between the slats of the car side when the lattice door is in a depending position, said bars being positioned over other slats of the car side when the door is extended upwardly.

In witness that I claim the foregoing I have hereunto subscribed my name this 23rd day of December, 1921.

ARGYLE CAMPBELL.
